UNITED STATES PATENT OFFICE.

JOSEPH BRESCH, OF ROSEMONT, NEW JERSEY.

THROW-OFF MECHANISM FOR RIBBON LOOMS.

Application filed February 14, 1922. Serial No. 536,604.

To all whom it may concern:

Be it known that I, JOSEPH BRESCH, a citizen of the United States, residing at Rosemont, in the county of Bergen and State of New Jersey, have invented new and useful Improvements in Throw-Off Mechanism for Ribbon Looms, of which the following is a specification.

This invention relates to throw-off mechanism for ribbon looms and the principal object is to provide means whereby "smashings" may be prevented.

Another object is to produce a device which will act instantly when anything goes wrong in the weaving, and will immediately effect a stopping or shutting down of the entire loom.

Another object is to produce a device of this nature which shall be simple of construction, cheap to manufacture, and highly efficient for the purpose for which it is designed.

With these and other objects in view, the invention resides in certain novel construction, and combination and arrangement of parts, the essential features of which are hereinafter fully described, are particularly pointed out in the appended claims, and are illustrated in the accompanying drawing, in which:

Figure 1 is a side elevational view of my improvement.

Figure 2 is a top plan view of the same.

Figure 3 is an end elevation of the same.

Like characters of reference refer to like parts in all views.

Referring to the drawing in detail, 10 represents a wheel driven by a belt 11 operable from any suitable source of power, the wheel 10 being arranged to frictionally drive wheel 12. The wheel 12 operates to cause the movements required in the loom. A link 13 connects the wheel 12 to a depending member 14 which is connected as at 15 with what is termed the "batten" 16. Mounted on the batten 16 is a rack bar 17 the racks of which operate the shuttles. All of this mechanism is old and well known in the art. The batten is moved back and forth by the mechanism above described and at the same time by means not shown but which are well known in the art, the rack bar 17 and its racks are moved at right angles to the movement of the batten.

55 A pin 18 is secured to move with the rack bar 17 and partakes of the movements of

both the rack bar and batten. The degree and size of this curve is different in different machines and for different widths of ribbon. A block 19 is provided which has the curvilinear contour of the movement of the pin 18 but is arranged a slight distance away from said pin. Fingers 20 extend from the curved periphery of the block 19 so as to give a flat face for the pin to work against when anything goes wrong as will presently be described. The block 19 is mounted at the upper end of arm 21 hinged to any suitable base member as at 22, and drawn normally into a vertical position by spring 23. A link 24 is connected to a flexible member 25 which is secured to a trigger 26. The trigger 26 is formed with a shoulder at 27 to hook over a pin 28. The lower end of trigger 26 is connected by a flexible line 29, guided through eyes 30 to the bottom of a brake member 31 carrying at its upper end any suitable braking means 32 adapted to contact with the peripheries of both wheels 10 and 12. A weight 33 is connected to the member 31 for driving it home when the trigger is released, and a spring 34 assists in this action and prevents any back lash.

In operation when anything goes wrong in one of the shuttles the rack 17 will stop, and through movement of the batten 16 will bring the pin 18 against the member 19 or one of its pins 20 so as to move the arm 21 against the tension of spring 23. This pulls on link 24 and line 25 and unhooks the trigger 26 whereupon the weight 33 and spring 34 drive the brake member 31 between the wheels 10 and 12 thereby stopping them instantly and the belt 11 throws itself from the wheel 10.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:

1. In a device of the class described, the combination of a pin for operation by a moving part of a loom, means for imparting a compound movement to said pin, a block having one of its faces provided with a

curved surface, hingedly mounted supporting means for said block, a spring for holding said supporting means in operative position, a trigger operable by said supporting means, a brake device, and driving mechanism for said loom adapted to be rendered inoperative by said brake device upon the releasing of said trigger.

2. In a device of the class described, the combination of a pin for operation by a moving part of a loom, means for imparting to said pin a compound movement, a block having one of its faces provided with a curved surface, hingedly mounted supporting means for said block, a spring for holding said supporting means in operative position, a trigger operable by said supporting means, a brake device, a weight connected to

said brake device, a spring connected to said brake device, and driving mechanism for 20 said loom adapted to be rendered inoperative by said brake device.

3. In a device of the class described, the combination of a pin for attachment to the rack bar of a loom, a hingedly mounted 25 block adjacent said pin, a plurality of pins projecting from said block and at right angles to said first mentioned pin for co-action with each other, a trigger operable by said block, a brake device operable upon the releasing of said trigger, and driving mechanism for said loom adapted to be rendered inoperative by said brake device.

In testimony whereof I have affixed my signature.

JOSEPH BRESCH.
